CLAIM

The ornamental design for a straw lid, as shown and described.

DESCRIPTION

FIG. 1 is a top perspective view of a straw lid, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a front perspective view showing the straw lid, in closed configuration of use;

FIG. 9 is another perspective view showing the straw lid, in open configuration of use; and,

FIG. 10 is a rear perspective view of FIG. 9.

All the broken lines in the drawings depict portions of the straw lid that form no part of the claimed design.
